ABSTRACT

In a suspension for a railway bogie or fourwheeled wagon an axlebox assembly has a face riding against a pedestal guide and supports the frame assembly through a suspension spring. A friction damper in the pedestal guide engages the face in line horizontally with the axle bearing. An upper spring abutment is supported by the frame assembly through to the pedestal by an inclined downwardly facing wedge surface so that the spring force loading the abutment results in a lateral force applied to the damper and rising in the axlebox assembly may comprise an axlebox in an inverted saddle suspended from a beam on or above the axlebox and frictionally engaged by the damper. The saddle provides for relative lateral movement of the axlebox. The spring abutment is provided by a pot-like spring housing with an integral surrounding collar with an upwardly facing wedge surface. The wedge surfaces engage frictionally or are separated by bonded rubber pads in combine shear and compression.

SNUBBED RAILWAY BOGIES

This invention relates to suspension systems for railway vehicles and is applicable to wagons of four wheeled type and to bogie vehicles. The invention relates particularly to spring mountings for axleboxes movable in or against pedestal guides and in which suspension springs are arranged alongside the pedestal guides to support a frame member of the vehicle on the axlebox.

Objects of the invention are to provide improved riding characteristics and to provide a suspension which is damped with a rising load characteristic, i.e., so that the damping force increases with the vehicle loading.

In one aspect of the invention, a suspension arrangement comprises a sprung frame assembly including a pedestal guide, an axlebox assembly having a face riding against the pedestal guide and a suspension spring disposed alongside the pedestal guide and between the frame assembly and the axlebox assembly, wherein a friction damper is arranged in the pedestal guide for frictional engagement with said face at a region approximately in line horizontally with the rotational axis of the axle bearing and wherein an upper spring abutment is supported by the frame assembly through an inclined surface in such manner that the spring force loading the abutment results in a lateral force urging the latter towards said face, which lateral force is applied to the damper so that the frictional damping force rises in proportion to the load on the frame assembly.

The axlebox assembly may comprise an axlebox in a saddle suspended from a beam on and above the axlebox, the saddle providing the face riding against the pedestal guide and frictionally engaged by the damper, the saddle also providing for limited lateral movement between the axlebox and the saddle, i.e., movements axially of the axle bearing.

In another aspect, a suspension arrangement comprises a sprung frame assembly including a pedestal guide, an axlebox assembly having a face riding against the pedestal guide and a suspension spring disposed alongside the pedestal guide and between the frame assembly and the axlebox assembly, a friction damper being arranged in the pedestal guide for frictional engagement with said face at a region approximately in line horizontally with the rotational axis of the axle bearing, the axlebox assembly comprising an axlebox in a saddle suspended from a beam on and above the axlebox, the saddle providing said face riding against said pedestal guide and frictionally engaged by the damper, the saddle also providing for limited lateral movement between the axlebox and the saddle, i.e., movement axially of the axle bearing.

According to the invention in a further aspect a railway bogie or four-wheeled wagon has combined suspension and damping means which comprise, for each axlebox assembly of the bogie or wagon, a suspension spring arranged at one side of the axlebox assembly, a friction damper arranged in a pedestal guide of the corresponding side frame of the bogie or wagon for frictional engagement with said one side of the axlebox assembly at a region approximately in line horizontally with the rotational axis of the axle bearing, and upper spring abutment means supported by the side frame through an inclined surface in such manner that the spring force loading the abutment means results in a lateral force urging the latter towards the axlebox as-

sembly, which lateral force is applied to the damper so that the frictional damping force rises in proportion to the load on the bogie or wagon.

In the case of a bogie having a conventional axlebox arrangement, with each of the four axleboxes sliding between spaced pedestal guides in the corresponding side frame, said suspension spring will normally be one of two similar springs disposed symmetrically on opposite sides of the axlebox concerned. However, only one set of spring abutment means and damper is required for each axlebox, these being arranged either on the inner side of or the outer sides of, the axleboxes to provide a balanced arrangement.

The invention is also applicable to radial arm type axleboxes, in which case each axlebox is associated with only one pedestal guide housing the corresponding damper on the side of the axlebox remote from the fixed fulcrum of the radius arm. The use of only a single pedestal guide is dictated by the necessity to provide suitable lateral characteristics, and the arm may be mounted on the fixed fulcrum through a bonded rubber bush permitting limited lateral movement of the wheel and the axle sets.

The abutment means may comprise what is hereinafter termed a "floating wedge pot," having a pot-like structure with a central bore in which the upper end of the spring is received and which acts as a spring guide. An integral surrounding collar at the lower open end of the pot has an upwardly facing wedge surface which is inclined upwardly toward the axlebox, this collar directly engaging the damper and the wedge surface being supported by said inclined surface of the side frame. These surfaces may be in direct frictional engagement, although in an alternative arrangement which obviates the effect of friction these surfaces are separated by bonded rubber pads which are placed in combined shear and compression to provide the horizontal reaction which loads the damper.

Said suspension spring engaging the wedge pot may be the only spring associated therewith, although an arrangement of springs may be employed with two springs separated by an intermediate member and effective in series under light load conditions and in parallel under full load conditions. This enables one spring to be used when the bogie is travelling light, i.e., in the tare condition, with both springs operative in the loaded condition.

The damper preferably comprises a damper friction pad which is mounted between portions of a split collet arrangement which grips the pad with a wedging action to urge the latter into frictional engagement with the axlebox. The collet arrangement is guided for horizontal movement in the pedestal guide and it may be directly engaged by the abutment means.

Four railway bogies and a wagon suspension representing illustrative embodiments of the invention will now be described by way of example, and with reference to the accompanying drawings in which:

FIG. 1 is a diagrammatic side view of the side frame of a bogie and axleboxes therein incorporating combined suspension and damping means,

FIG. 2 shows diagrammatically a sectional view of one axlebox suspension in the end of a bogie side frame and illustrative of a first embodiment,

FIGS. 3 and 4 illustrate details of the suspension of FIG. 2,

FIG. 5 illustrates a second embodiment comprising an alternative suspension spring,

FIGS. 6 and 7 are diagrammatic perspective and sectional views respectively of another axlebox suspension representing a third embodiment,

FIGS. 8 and 9 are diagrammatic views in elevation and plan respectively of an axlebox suspension representing a fourth embodiment,

FIGS. 10, 11 and 12 are diagrammatic views in side elevation, end elevation and plan respectively of an axlebox suspension for a four-wheeled wagon, and

FIGS. 13 and 14 illustrate details of the axlebox suspension of FIGS. 10, 11 and 12.

As shown diagrammatically in FIG. 1, the first three embodiments have conventional axlebox arrangements, with each axlebox 10 slidably supported between spaced pedestal guides 11 in the corresponding side frame 12 of the bogie. A symmetrical arrangement of suspension springs 13 and 14 is employed for each axlebox 10, the springs 13, 14 having bottom seatings on webs 15 of cradles 16 which are parts of the axlebox assemblies. Combined suspension and damping means apply a frictional damping force to the outer side of each axlebox 10, the corresponding damper 17 being mounted in the pedestal 11 at that side. This provides a symmetrically balanced arrangement with the whole of the suspension located on the centre line of the axlebox journal which is important with wheel and axle sets having self-aligning bearings, although the invention is not confined to such an arrangement. In each case the combined suspension and damping means for one axlebox only will now be described.

In the first embodiment shown in FIG. 2, a single suspension spring 13, 14 is employed at each side of the axlebox 10, the upper end 18 of the spring 14 at the outer side being received in a floating wedge pot 19, detailed in FIG. 4, which has a collar 20 providing a wedge surface 21 and which projects into a housing 22 cast in the corresponding side frame 12 alongside the adjacent pedestal guide 11. Around the lower end of this housing 22 the side frame 12 has, as shown in FIGS. 2 and 3, a surface 23 which is inclined upwardly towards the axlebox 10 and against which the upper wedge surface 21 of the wedge pot collar 20 is directly supported. At the inner side this collar 20 has a flat surface 24 which engages the back face of a circular collet arrangement 25, whereby to apply, to a damper pad 26 engaged by the collet, a damping force which increases with suspension load. A rubber ring 27 which surrounds the wedge 19 locates it in a generally central position within the housing 22 and prevents wear, while allowing the small floating movement which is essential to operation and to take up wear of the damper 17 comprising the collet 25 and the damper pad 26.

The collet arrangement 25, detailed in FIG. 4 and of hollow section shown in FIG. 2, is split radially into three portions *a*, *b*, *c* of saddle-like radial cross section and slidably in a horizontal guide bore 28 (FIG. 2) in the pedestal guide 11. At the back end the limbs of the collet portion *a*, *b*, *c* are closely spaced so as to engage to prevent undue tilting or twisting of the portions such as would result in jamming in the guide bore 28, and the front limbs of the portions *a*, *b*, *c* together present a concave frusto-conical mouth 29 in which a complementary boss 30 at the back of the damper pad 26 is received. For good wedging action, flats or recesses 30a are formed on the boss 30 and matching flats are

formed in the collet portions *a*, *b* and *c*. This pad 26 is of rectangular shape with a frictional surface which engages the adjacent outer side of the axlebox 10.

The second embodiment is similar to the first except that each suspension spring 13, 14 is replaced by two springs which operate in series in the tare condition and in parallel in the loaded condition. The wedge pot 19a for the outer side of the frame 12 is shown in FIG. 5, the two springs replacing spring 14 of FIGS. 1 and 2 being designated 31 and 32. The lower end of the upper and weaker spring 31 is received in an intermediate pot member 33 and abuts a plunger 34 in the bottom of the pot member 33. The latter has an open top with an external flange 35, which flange 35 provides the upper abutment for the lower and stronger spring 32 which fits closely within the wedge pot 19a. As the vehicle is loaded, the intermediate member 33 engages the closed end of the wedge pot 19a or, on the inner side of the axlebox not provided with a damper, engages a suitable abutment of the side frame 12. Also the plunger 34 engages the web 15 so that the spring 31 is operative in parallel to the spring 32.

The third embodiment, illustrated in FIGS. 6 and 7, is generally similar to the first except that the wedge surface 21a on the pot collar 20 does not directly engage the inclined supporting surface 23a on the side frame 12. Instead these surfaces 21a and 23a are separated by bonded rubber pads 36, disposed on opposite sides of the spring 14 and lying force-and-aft of the bogie, these pads 36 operating in combined shear and compression to provide the horizontal reaction which loads the damper pad 26 of the damper 17.

The fourth embodiment, illustrated in FIGS. 8 and 9, includes radial arm type axleboxes. Each axlebox 40 is disposed at one end of a corresponding radius arm 41 which is supported about a fixed fulcrum by a bonded rubber bush 42. Adjacent the free end of the arm 41 the axlebox 40 is engaged by a friction damper 17 comprising a damper pad 26 mounted in an adjacent pedestal guide 11a with the combined suspension and damping means generally as described in connection with the first embodiment. The radius arm 41 is continued below the axlebox 40 to provide a lower spring abutment 43, and side webs 44 which connect this abutment 43 to the axlebox 40 are respectively disposed at opposite sides of the pedestal guide 11a which is relatively narrow laterally of the vehicle. Sufficient clearance is provided to allow adequate controlled lateral movement of the wheel and axle sets, which movement is accommodated by the fulcrum bushes 42.

It will be appreciated that the upper spring abutment means 19 of the invention, which operate by virtue of the inclined wedge surface 23 to load the associated friction damper 17, do not normally move vertically with respect to the side frame. Such slight vertical movement as occurs corresponds to small lateral float which may occur, for example to take up wear of the friction surfaces, and is very small. There is no material or continuous vertical movement associated with suspension movement.

FIGS. 10 to 13 illustrate one of four similar axlebox mountings for a four-wheeled wagon. Referring to these figures, a main side frame member or sole-bar 50 carries a sub-frame 51 including a pair of pedestal guides 52, 53 between suspension spring housings 54, 55. The axlebox 56 is located between the pedestal guides 52, 53 but is part of an assembly comprising an

upper beam 57, fixed to the top of the axlebox 56, and an inverted saddle 58, suspended from the beam 57 by tie-rods 59 which have horizontal pivotal axes in the beam 57, and fulcrum pads 60 and nuts 61 beneath the saddle. The tie-rods pass freely through the suspension spring housings 54, 55 and suspension springs 62 and 63, and the suspended saddle 58 provides lower abutments 64, 65 for the suspension springs. The arms of the saddle 58 provide pedestal bearing surfaces for the axlebox 56 and have flanges 66 each with a clearance of about $\frac{3}{4}$ inch with respect to the axlebox so that the axles have limited axle freedom of movement in relation to the frame 50 and sub-frames such as 51, this relative movement being permitted by swinging movement of the saddle 58 and tie-rods 59 relative to the beam 57. The flanges 66 of the saddle 58 also embrace the pedestal guides 52, 53 and are a sliding fit thereon. Hence the axlebox assembly provides for vertical suspension movement of the sub-frame by sliding of the pedestal guides 52, 53 in the saddle, while the axlebox has relative horizontal movement with respect to the saddle. The suspension springs 62 and 63 are mounted in a manner similar to that in the bogie described with reference to FIGS. 1 to 4, the saddle 58 providing the lower abutments. One spring 63 provides damping dependent on wagon loading in a manner similar to that in said bogie, but the damping pressure is applied not directly to the axlebox but to the saddle 58. To this end, a wedge-pot 67 providing the upper abutment for the suspension spring 63 applies lateral pressure through a collet assembly 68 to a friction pad 69 engaging the web 70 of the adjacent arm of the saddle 58.

A spring-loaded friction damper may be provided between the top of the axlebox and the under surface of the sub-frame immediately above the axlebox, or between the under side of the axlebox and the saddle 58, for damping the relative motion of the axlebox axially of the axle bearings. The described axlebox assembly provides load-dependent damping of a balanced two-spring suspension, and an axlebox of existing pattern having relative lateral motion independent of the vertical suspension. Such assemblies embodied in four-wheeled wagons make for high-speed running of such wagons.

I claim:

1. A railway vehicle having a suspension arrangement comprising a sprung frame assembly which includes a pedestal guide, an axlebox assembly having a face which engages the pedestal guide, a friction damper and a suspension spring the upper end of which engages a spring abutment supported by the frame assembly and the lower end of which engages the axlebox assembly, said spring abutment having a first surface that acts against a surface of the frame assembly which is inclined to the vertical and which surrounds the suspension spring and a second surface which is directed towards said face of the axlebox assembly and engages the friction damper, the friction damper being arranged in the pedestal guide and positioned between the second surface of the spring abutment and said face of the axlebox assembly so that the spring force loading the abutment results, through interaction of said first surface thereof with said inclined surface of the frame assembly, in a lateral force urging the spring abutment towards the damper to bias the latter against said face of the axlebox assembly, the damper including a part having surface means engaged by complementary sur-

face means of the pedestal guide in such manner that the damper is prevented from movement in the vertical direction and the force transmitted to the face of the axlebox assembly is a purely lateral force.

5 2. A railway vehicle according to claim 1, wherein the axlebox assembly comprises an axlebox in an inverted saddle suspended from a beam on and above the axlebox, the saddle providing the face which engages the pedestal guide and permitting limited relative movement between the axlebox and the saddle in a direction axially of the axlebox bearing.

10 3. A railway vehicle according to claim 1, wherein there are two axlebox assemblies each carried on a radius arm and each associated with a pedestal guide which houses a corresponding friction damper positioned on that side of the axlebox assembly remote from the fulcrum of the corresponding radius arm.

15 4. A railway vehicle according to claim 3, wherein the means for mounting each radius arm on its fulcrum includes a bonded rubber bush which acts to control movement of the wheel and axlebox sets.

20 25 5. A railway vehicle according to claim 1, wherein the part of the damper having the surface means engaged by complementary surface means of the pedestal guide is of generally cylindrical form and said complementary surface means comprises the surface of a cylindrical bore.

30 6. A railway vehicle according to claim 5, wherein said part is a split collet which, together with a friction pad constitutes the friction damper, the collet having portions which grip a boss on the pad with a wedging action to urge the pad into frictional engagement with the axlebox assembly.

35 7. A railway vehicle according to claim 1, wherein the spring abutment comprises a pot-like structure on which said surface is disposed and which has a central bore in which the upper end of the spring is received.

40 8. A railway vehicle according to claim 7, wherein the lower end of the pot-like structure has an integral surrounding collar having an upwardly facing wedge surface inclined upwardly towards the axle box assembly, said collar acting against the damper and the wedge surface constituting said first surface of the spring abutment.

45 9. A railway vehicle having a suspension arrangement comprising a sprung frame assembly which includes a pedestal guide, an axlebox assembly having a face which engages the pedestal guide, a friction damper and a suspension spring the upper end of which engages a spring abutment supported by the frame assembly and the lower end of which engages the axlebox assembly, said spring abutment comprising a pot-like structure with a central bore in which the upper end of the spring is received, said pot-like structure having an external collar which provides a wedge surface which surrounds the spring and is inclined to the vertical and acts against a cooperating surface of the frame assembly and an abutment surface which is directed towards said face of the axlebox assembly and engages the friction damper, the friction damper being positioned between said abutment surface of the collar and said face of the axlebox assembly with the arrangement such that the spring force loading the abutment results, through interaction of the wedge surface and the cooperating surface of the frame assembly, in a lateral force being transmitted to the damper to bias the latter against said face of the axlebox assembly.
